EX

OR D 14,070

Design No. 14,070, dated July 10, 1883.

UNITED STATES PATENT OFFICE.

ROBERT F. MEISSNER, OF CHICAGO, ILLINOIS, ASSIGNOR TO W. W. KIMBALL COMPANY, OF SAME PLACE.

DESIGN FOR A CABINET-ORGAN CASE.

SPECIFICATION forming part of Design No. 14,070, dated July 10, 1883.

Application filed March 5, 1883. Term of patent 7 years.

To all whom it may concern:

Be it known that I, ROBERT F. MEISSNER, a citizen of the United States, residing at Chicago, in the county of Cook and State of Illinois, have invented and produced a new and original Design for Cabinet-Organ Cases, of which the following is a specification, reference being had to the accompanying engraving, forming part thereof, wherein is shown a perspective view of my newly-designed case.

My design is provided with a central raised back, A, decorated in front by carved rosettes *a* and engraved ornamentation *a'*. The outline of the top edge is square at the corners *a*² and scalloped over the rosettes. At the sides *a*³ this back is cut in irregular outline. In front of this back is a drawer, B, and an inclosure, B', formed of the filigree-work *b* in front and spindle-railing *b'* at the sides, united at the corners by posts *b*². Below these posts, and at either side of the drawer, are carved volutes *b*³. The front of the drawer is ornamented with buttons *b*⁴ and projections *b*⁵, and recedes downwardly. The posts *b*² are fronted with rosettes at *b*⁶. The top board, C, of the case is surmounted at either end by a railing, *c*, and these railings abut the rosetted projections *c'* at the back corners.

Below the top board, C, is the ogee molding *d*, the carved frieze *d'*, and the paneled door E. The panel of this door is veneered with natural wood ornamented around its margin with engraved lines, dots, &c., *e*.

At either side of the door are pilasters E', with carved columns *e* inserted, and at the side, and outside the pilasters, are open-work doors F, (which, however, may be stationary panels instead of doors.)

At the outer corners, adjoining the doors or panels F are pilasters F', having the carved columns *f*, forming part thereof.

The upper side panel, G, is ornamented by carved or engraved work, as shown.

H is the dividing-board between the closets in the top and the organ beneath. Below it, and above the key-board lid I, is a line of

scalloped or recessed molding, *h*. The lid has a central panel of natural wood ornamented by engraving in fanciful designs. At the sides of this part of the case are brackets J, the formation of which is clearly indicated. They have at the top a line of shell-work, *j*, and at the center a carved decorated column, *j'*, surmounted by a capital, *j*². The side of the bracket is ornamented at *j*³ by engraved lines, at *j*⁴ by buttons, and at *j*⁵ by an engraved coil.

The lower side panel, K, is ornamented by molded lines *k*, and at the front of it is a straight post or pilaster, K', having horizontal ribbed bands *k'*.

The key-slip front L is of filigree open-work, consisting of leaves and encircling and connecting vines. The carved frieze M forms the front of the action-support.

The drawer-front B and inclosure B' stand out boldly from the top of the case, and form a prominent part of my design. It is not necessary, of course, that the part B should be actually the front of a drawer. I have described it as such because the space behind it has been utilized as a drawer in the cases which have been made embodying my design.

I claim—

1. The design for cabinet-organ cases here- 75 in shown.
2. In a cabinet-organ case, the design of the raised back A, substantially as specified.
3. In a cabinet-organ case, the design of the inclosure B', substantially as shown. 80
4. The corner-posts *b*², fronted by the rosettes *b*⁶, substantially as shown.
5. The drawer - front B, substantially as shown.
6. The rosetted corner projections, *c'*, sub- 85 stantially as shown.
7. The doors or panels F herein shown.
8. The corner-pilasters F' herein shown.
9. The columned portion of the bracket J— viz., the parts *j*' and *j*²—substantially as shown. 90
10. The key-slip front L herein shown.
11. In a cabinet-organ case, the design of the pilaster E' with the carved column inserted therein, substantially as shown.

12. In a cabinet-organ case, the design of the corner-pilasters F' with the carved - column inserts therein, substantially as shown.

13. The action - support front M herein
5 shown.

14. In a cabinet-organ case, the design of the upper side panel, G, substantially as shown.

15. In a cabinet-organ case, the design em-

bracing the filigree front of the key-slip and 10
the carved frieze front of the support thereof,
substantially as shown.

Chicago, March 2, 1883.

ROBERT F. MEISSNER.
